UNITED STATES PATENT OFFICE

JOSEPH HENRY ROE, OF MARKET HARBOUROUGH, ENGLAND

BRUSH FOR CLEANING PIPES AND TUBES

Application filed December 9, 1927, Serial No. 238,389, and in Great Britain December 11, 1926.

This invention relates to brushes for cleaning pipes and tubes internally and concerns more especially though not exclusively brushes for cleaning pipes connected with milk pasteurizing and sterilizing apparatus.

Brushes for the above mentioned purposes usually consist of a shank or hub from which the bristles, fibre or bass radiate and are distributed longitudinally in spiral form or in a succession of rings the brush in use being passed longitudinally through the pipe or tube so as to act upon the interior thereof. In a form of brush as commonly used the bristles or equivalent are held in a shank of twisted wire.

The difficulty with brushes of this type is to obtain sufficient brushing action on the inside of the tube or pipe. When the bristles are attached to a twisted wire or a shank of comparatively small diameter they have a tendency to lie down when passing through the tube, or in other words owing to their length they are not stiff enough to remain erect and operate with the strong scrubbing action desired on the inside of the tube. To overcome this difficulty, cleaning brushes have been made with a hub or shank of comparatively large diameter furnished with short stiff bristles but these brushes have been open to objection for the reason that they soon become clogged up in use this being due to the fact that the space about the large hub was not sufficient to accommodate the scale or other matter removed from the interior of the pipe by the bristles.

The present invention comprises a brush of improved construction for the aforesaid purpose and is characterized by the provision in combination with the bristles or the like of means to afford support for the latter when the brush is in use whereby they are rendered more effective in action.

The invention may be carried out by providing on the hub or shank of the brush one or more discs or like members of smaller diameter than the brush which serve to support the bristles against lateral yield when passing through the pipe or tube. According to a modification one or more discs may serve to carry the bristles as well as support

them as aforesaid. For this purpose said disc or each disc may be formed with a rim in which the bristles are secured, and a flange extending beyond the rim to afford the required support to the bristles.

In a brush for use with a rotary motion such as may be imparted mechanically there may be provided one or more discs or the like formed, furnished with, or carrying members arranged to extend longitudinally of the brush between the bristles and thereby to support the latter against yield circumferentially when the brush is in use.

In order that the invention may be more clearly and readily understood practical examples thereof will now be described with reference to the accompanying drawings wherein

Figure 1 is a side elevation of a brush wherein the bristles are secured in a wire shank, and discs are employed to limit the lateral yield of the bristles.

Figure 2 is a section taken on line II-II of Figure 1.

Figure 3 is a sectional side elevation of part of a brush wherein the bristles are carried as well as supported by discs.

Figure 4 is an end elevation partly in section of the construction shown in Figure 3.

Figure 5 is a sectional side elevation of a brush employing discs designed to support the bristles against circumferential yield.

Figure 6 is sectional end elevation of this brush.

Figures 7 and 8 show a modification hereinafter described.

Figure 9 is a side elevation of a brush wherein the bristles are supported circumferentially by longitudinal wires carried by the discs.

Figure 10 is a cross section of the same on the line X-X of Figure 9.

Figure 11 is a face view of one of the discs having a modified centre.

Figure 12 is an edge view of said disc on a wire shank.

According to that form of the invention illustrated in Figures 1 and 2, I provide, in a brush having the bristles 1 held by a shank 2 of twisted wire in the well known manner, a

plurality of circular discs 3 situated at intervals apart. These discs are of less diameter than that of the brush, and are intended to constitute supports for the bristles near their outer ends without however, touching the inside of the pipe or tube in which the brush is used. When the brush is thrust by an endwise movement through the pipe or tube and the bristles bend or tend to lie down under this action, the discs 3 limit the bending or yield of the bristles and thereby stiffen the ends which project beyond the peripheries of the discs so that they operate more effectively on the inside of the pipe or tube.

15 The discs 3 may be fastened upon the shank 2 in any convenient manner but preferably they are rotatable and also capable of tilting (they may for instance fit loosely) so that they can adjust themselves to requirements 20 when the brush is in use.

I find that the desired effect can be readily obtained by means of metal discs located among the bristles and spaced one inch apart or thereabouts, although the spacing may 25 vary according to the size of the brush and the nature of the bristles or equivalent therein, the discs having central holes 4 by which they are threaded upon the shank and kept in place by the bristles.

30 The discs may have holes or openings (not shown) therein in addition to the central hole, and they may be composed of any suitable material it being understood that the bristles when bent from the erect or radial 35 position by contact with the interior of the pipe rest against the discs especially the peripheral portion thereof and are thereby supported against further yield. This produces the effect of short stiff bristles without 40 however, the disadvantage of such bristles.

The discs are applied so that the bristles are not tightly compressed or compacted between them there being a certain amount of yield of the bristles allowed and also space 45 for accumulation of dirt without clogging.

In carrying the invention into practice as illustrated in Figures 3 and 4, I fix the bristles in discs 5 each of which has an enlarged rim 6 with a flange 7 extending beyond the 50 same on one side thereof to support the bristles, which, of course, extend beyond the flange, near their outer ends. Conveniently bunches of bristles doubled to form tufts 8 are inserted in holes or sockets 9, formed radially at suitable intervals apart in the rim 6 and held in position by means of wire loops 10 formed by threading wire in and out of the holes or sockets continuously, as represented in Figure 4. A brush of any desired 55 length may be formed by mounting a plurality of these discs at suitable distances apart, determined for example by distance pieces 11 or central bosses on the discs on a shaft or spindle 12 as represented in Figure 60 65 3, for which purpose said discs are provided

with holes 13 and clamping the discs in position by nuts (not shown) or other convenient means. As will be readily understood the flanges 7, when the brush is operating axially in a pipe or tube, afford support to the bristles in exactly the same manner as the discs 3 hereinbefore referred to.

Considering now that form of the invention illustrated in Figures 5 and 6, as applied for example, to a brush wherein the bristles 1 are held by a shank of twisted wire 2 as aforesaid, but which brush is intended for rotary operation or rotary and endwise movement, I provide discs 14 each having projecting at right angles from one side thereof a plurality of equally spaced radial members 15. These members may be formed integrally such as by a pressing or punching operation, or may consist of separate right angular pieces riveted in position as shown in Figures 7 and 8. The said discs are of a smaller diameter than the brush and are provided with holes 16 whereby they can be threaded upon the shank 2. When the discs are located among the bristles at the desired distances apart the radial members extend longitudinally between the bristles 1 with their outer ends below the outer ends of the bristles. Consequently when the bristles are bent circumferentially from the erect position due to rotation of the brush within a pipe or tube they will be prevented from yielding unduly owing to the resistance offered by the radial members. Incidentally the peripheries of the discs would support the bristles against lateral yield in the event of the brush being subjected to end thrust.

Obviously this form of the invention might be carried out in a brush wherein the bristles are secured in discs 5 as already described, i. e. by forming or providing radial right angular projections on the flanges 7.

In Figures 9 and 10 I illustrate another form of means for supporting the bristles in a circumferential direction. These means consist of wires 17 passed through holes 18 formed in discs 19 near the periphery thereof as shown in Figure 11. The wires 17 are disposed longitudinally of the brush and pass between the radial bristles as shown in Figure 10 to serve as supports when the brush operates with a rotary motion in a pipe or tube. In this case the discs 19 also serve to afford lateral support for the bristles when the brush operates in an axial direction. The wires 17 may be secured in a suitable manner, e. g. by riveting or bending over the ends on the outside of the endmost discs. Wires may be similarly carried by the discs 7.

I may, if desired, secure the discs on the shank and adopt for this purpose any suitable means. When the brush is to operate with a rotary motion and the discs form or carry devices to support the bristles in a circumferential direction it is desirable to pre-

vent the discs from turning on the shank. To this end I may, instead of making a circular hole such as 16 in the disc, provide two slots therein such as 20 (Figure 11) shaped to suit the wire. The two strands of wire of which the shank 21 is composed are passed one through each slot and twisted together on opposite sides of the disc as shown in Figure 12. This secures the disc and prevents turning and lateral movement thereof on the shank. The discs 3 and 14 may be secured in the same manner. When the discs have round holes such as 16 I may insert pins or nails transversely through the shank to keep the discs from shifting laterally along the shank.

The hub or shank of the brush can be made small thereby providing adequate space for the accommodation of the scale or matter removed from the pipe.

20 What I claim then is:—

1. A circular brush comprising a shank composed of wires twisted together, bristles radially disposed thereon, and discs on said shank to afford lateral support for the free portion of the bristles under operation of the brush in an axial direction.

2. A circular brush comprising a shank, bristles radially disposed thereon, discs on said shank to afford lateral support for the free portions of the bristles, and means carried by the discs extending longitudinally between the free portions of the bristles to support same in a direction circumferentially of the brush.

3. A circular brush comprising a shank, bristles radially disposed thereon, discs on said shank, and wires running longitudinally of the brush and through the free portions of the bristles, said wires being carried by the discs and serving as supports for the bristles in circumferential direction.

4. A circular brush comprising a shank, bristles radially disposed thereon, discs on said shank, and wires extending longitudinally of the brush and through holes in said discs to afford support for the free portions of the bristles in a direction circumferentially of the brush.

5. A circular brush comprising a shank composed of wires twisted together, bristles disposed radially on the shank, discs on said shank to afford support for the free portions of the bristles and limit their bending due to operation, and means to secure said discs at intervals apart on the shank.

6. A circular brush comprising a shank formed of wires twisted together, bristles on said shank, and discs on the shank to afford support for the free portions of the bristles in the direction of operation of the brush, the wires of the shank passing through separate holes in the discs to secure the latter in position.

7. A circular brush for cleaning pipes and

tubes internally, comprising a shank, bristles radially disposed thereon, circular discs located at intervals apart on the shank and of a diameter substantially less than the brush, said discs being so arranged that the portions 70 of the bristles between their extremities and the shank are free to yield by bending under operation of the brush, wires disposed longitudinally of the brush and carried by the discs the said wires being spaced apart circumferentially of the brush amongst the free portions of the bristles to permit a limited bending yield thereof and serve as abutments to support the said free portions of the bristles during rotary operation of the brush. 80

In testimony whereof I affix my signature.

JOSEPH HENRY ROE.
